CONTAINER

Richard James Greenleaf, II, Ipswich, Mass., assignor of one-half to Victor H. Barwood, Brookline, Mass.

Application June 27, 1941, Serial No. 400,017

11 Claims. (Cl. 229—32)

The present invention relates to containers, and more particularly to containers for sandwiches and the like.

When the dispenser sells sandwiches made from round bread rolls, like egg and hamburger sandwiches, he is frequently troubled by the fact that the egg, the meat or other juices drip from below the sandwich, with consequent possible damage to the customer's clothes. This difficulty may be overcome by dispensing the sandwich in a container provided with a bottom wall for collecting the drippings. Containers, however, have not only bottom walls, but side and end walls, as well. When the sandwich is retained in the container during eating, the side walls, if high enough, are in the way, so as to prevent further biting into the sandwich when less than half consumed; and if the side walls are low, they do not afford a sufficient grip for holding the sand-

1. It has accordingly been proposed to provide further biting area by recessing the sides of the container. This proposal has here- 20 been made, however, in connection with containers having pointed, or unstable, bottom walls, adapted more particularly for sandwiches with square corners. For round sandwiches, of course, containers of this kind are not practicable because, when they are set down, the drippings leak out of the container by way of the end or side walls. The dispenser is thus compelled to hold the container, with the sandwich therein, in his hand until he actually delivers it to the customer; and the latter similarly dares not place it, even temporarily, on a counter or a table, but must keep it in his hand until the sandwich has been consumed, or until the container and its remaining contents are ready to be thrown into a waste-receptacle.

An object of this invention, accordingly, is to provide a container that, though having more general utility, is adapted particularly for a round-roll sandwich.

With the end in view of facilitating packaging and stacking, and to occupy a minimum of space during storage and shipping, a further object of the invention is to provide a container of the above-described character that may be made from a novel flat or knocked-down blank.

Unless the container is readily assembled from its blank, of course, it can not be commercially successful. Another object, therefore, is to provide a blank for which the container may readily be folded into the desired shape from its flat-blank form, as occasion may require.

A further object is to make a container and a blank therefor that shall be cheap to manufacture and highly efficient.

Other and further objects will be explained hereinafter, and will be particularly pointed out in the appended claims.

The invention will now be more fully described in connection with the accompanying drawing, in which Fig. 1 is a plan of a novel blank out of which the novel container may be formed; and Fig. 2 is a perspective of the container made from the blank of Fig. 1.

The novel container of the present invention, as well as the blank out of which it may be formed is generally designated at 2. The blank 10 may be constituted of thick paper, cut along the full lines, and scored along the dotted lines, of Fig. 1. The container is shown provided with a flat closed bottom wall 82 that serves as a stable base upon which the container is adapted to rest stably. This bottom wall is constituted of a centrally disposed substantially rectangular bottom-wall portion 82 of the blank. The long sides of the rectangle are foldably provided with side-wall-portions 4 and 8, respectively the former being foldably disposed along the scored line 6 and the latter along the scored line 10. The container is thus provided also with closed side walls 4 and 8, as well as end walls 80 and 84 connecting the side walls. The oppositely disposed side walls 4 and 8 are separated from the bottom-wall portion by scored lines 6 and 10, respectively, and the oppositely disposed end walls 80 and 82 by scored lines 20 and 30, respectively. The end-wall portions 80 and 84 are foldably disposed along the scored end lines 20 and 30 and the side-wall portions along the scored end lines 6 and 10 of the bottom-wall portion 82. At the top, the container is open. The container is of rectangular cross-section in planes parallel to the bottom wall 82, but the open top is relatively long compared to the relatively short bottom. In longitudinal cross-section, the container has the shape of a trapezoid, with the lower shorter base of the trapezoid closed and the upper longer base open. Along the sides of the trapezoid, the container is provided with somewhat trapezoidal end walls that slope between the ends 20 and 30 of the closed bottom wall 82 and the ends 58 and 64 of the open top.

45 At the top open end of the container, the sides 4 and 8 are each shaped into circular or other arcuate form to provide the sides of the contained, at the top, with oppositely disposed recesses. The circular arcs 70 and 76 of the respective sides 4 are shown concentric and of the same diameter.

In this container, though its open top, an egg, a hamburger, or other sandwich made from a round roll may be placed, so as to permit the upper portion of the sandwich to project above the open top thereof. The sandwich drippings will be collected in the bottom of the container. The purchaser may thus consume the sandwich from the top, without danger of the drippings getting on to his clothes. He may bite into parts of the

sandwich exposed above the curved sides 10 and 16 that could not be reached if these curved sides were straight. At a later time, after these parts of the sandwich have become consumed, the remaining portion of the sandwich, at the bottom of the container, may be pushed upward with the fingers from below, thus causing the sandwich to rise up in the container to permit further consumption thereof.

Because round-roll sandwiches are not usually of uniform thickness, but have more body in the center than along the periphery, the open upper end of the container is rendered somewhat wider than the bottom. To this end, the upper edges 58 and 64 of the end walls 80 and 84, respectively, are made wider than their respective lower edges 20 and 30, at the scored lines of junction with the bottom wall 82. The rectangle at the open top of the container is thus wider than that at the closed bottom wall. This construction serves a further purpose in that it enables stacking the container each inside its lower neighbor after they have become folded from their blanks.

A flap 12 is separated from the end-wall portion 80 by a scored line 14 along which it is foldable. Oppositely disposed to this flap 12 is a flap 16 foldably disposed with respect to the end-wall portion 80 along a scored wall 18. Similar oppositely disposed flaps 22 and 26 are similarly foldably disposed along scored edges 24 and 28, respectively, of the end wall 84.

The outer edge 68 of the flap 12 is separated from the edge 58 of the end-wall portion 80, by an edge 56 and tapers outward therefrom. The flap 16 is similarly provided with a similarly tapering outer edge 74 separated from the edge 58 by a similar edge 60. The flap 22 is similarly provided with a similarly tapering edge 72, separated from the edge 64 of the end-wall portion 84 by an edge 62, and the flap 26 is likewise provided with an edge 78 tapering outwardly from the edge 64 of the end wall 84, but separated therefrom by an edge 66.

The flap 12 terminates, at its end opposite to the edges 56, 58, in a tongue that is separated from the body of the flap 12 by a slit 40. The flap 16 similarly terminates, at its end opposite to the edges 60 and 58, in a tongue that is separated from the body of the flap 18 by a slit 44. The flaps 22 and 26 are similarly provided with terminating tongues, respectively separated from the bodies of the respective flaps by a slit 48 and a slit 52.

The outer curved margin 10 of the side wall portion 4 is provided with two slits 42 and 50 for respectively receiving the respective tongues of the flaps 12 and 22, as illustrated in Fig. 2, when the blank is folded into the form of a container. The outer curved margin 16 of the side-wall portion 8 is similarly provided with slits 46 and 54 for respectively receiving the tongues of the flaps 16 and 26, respectively. The tongues and the slits in which they are received cooperate to hold the blank, when folded, in the form of a container. The end-wall portions 80 and 84 constitute the oppositely disposed end walls of the container. The oppositely disposed side walls of the container, however, are constituted of the side-wall portions in cooperation with the corresponding flaps.

The outer edges 58 and 64 constitute the outer boundaries of the end walls 80 and 84 of the container. The outer edges 68 and 72 of the flaps 12 and 22, together with the outer edge 70, constitute the outer boundary of the side 4 of the container.

The outer edges 74 and 78 of the flap 16 and 26 and the outer edge 76 of the side-wall portion 8 similarly constitute the outer boundary of the side 8 of the container.

5 The outer edges 10 and 16 of the side-wall portions 4 and 8 taper correspondingly to the tapering edges of the flaps 12, 22 and 16 and 26, respectively. These taper from the center outward, so as to merge into the tapers of the respective flaps, 10 thus to constitute, with the tapering edges and the tongues of the respective flaps, the oppositely disposed recesses in the sides of the container before mentioned. By reason of this construction, these arcuate recesses are caused to taper continuously from near the edges 58 and 64 of the end walls 80 and 84, respectively, toward the bottom wall 82. The edges 56, 60, 62 and 66, however, are shown substantially parallel to the bottom wall 82.

Modifications will occur to persons skilled in the art, and all such are considered to fall within the spirit and scope of the invention, as defined in the appended claims.

What is claimed is:

1. A sandwich container having substantially the shape, in longitudinal cross-section, of an equilateral trapezoid, the container being closed by a flat bottom wall along the shorter base of the trapezoid upon which the container is adapted to rest stably, the container being open along the longer base of the trapezoid, the container having flat trapezoidal outwardly flaring end walls along the sides of the trapezoid sloping between the ends of the bottom wall and the top, the end walls being wider at the top than at the bottom, the container having flat side walls of substantially the same length as the length of the bottom wall connecting the end walls, the side walls being provided at the top of the container with oppositely disposed recesses curving from 35 near both end walls towards the bottom wall of the container, the container being of substantially rectangular cross-section in planes parallel to the bottom wall, and the rectangle at the open top being wider than the rectangle at the closed bottom, a sandwich being adapted to be confined in the container by the bottom, the end walls and the unrecessed portions of the side walls, the drippings from the sandwich being adapted to be collected in the bottom of the container between the lower portions of the end walls and the lower unrecessed portions of the side walls, and the unrecessed portions of the side walls providing an area for gripping the container with the sandwich therein.

2. A foldable-container blank comprising a centrally disposed flat bottom-wall portion having oppositely disposed ends and oppositely disposed sides, flat end-wall portions foldably disposed along the ends and each having oppositely disposed foldable flaps, flat side-wall portions of substantially the same length as said bottom wall foldably disposed along the sides and each provided with means for cooperating with the flaps to hold the blank, when folded, in the form of a container having outwardly flaring end walls, the bottom-wall portion constituting the flat bottom wall of the container, the end-wall portions constituting oppositely disposed flat end walls of the container, the side-wall portions and the flaps 70 constituting oppositely disposed flat sides of the container, the outer edges of the end-wall portions constituting the outer boundaries of the end walls of the container, the outer edges of the side-wall portions and of the flaps constituting the outer boundaries of the sides of the container,

the outer edges of the flaps tapering outwardly from near the outer edges of the end-wall portions and said flaps cooperating with said flat side-wall portions to form oppositely disposed recesses tapering from near both end walls toward the bottom wall.

3. A foldable-container blank comprising a centrally disposed flat bottom-wall portion having oppositely disposed ends and oppositely disposed sides, flat end-wall portions foldably disposed along the ends and each having oppositely disposed foldable flaps, flat side-wall portions of substantially the same length as said bottom wall foldably disposed along the sides and each provided with means for cooperating with the flaps to hold the blank, when folded, in the form of a container having outwardly flaring end walls, the bottom-wall portion constituting the flat bottom wall of the container, the end-wall portions constituting oppositely disposed flat end walls of the container, the side-wall portions and the flaps constituting oppositely disposed sides of the container, the outer edges of the end-wall portions constituting the outer boundaries of the end walls of the container, the outer edges of the side-wall portions and of the flaps constituting the outer boundaries of the sides of the container, the outer edges of the flaps tapering outwardly from near the outer edges of the end-wall portions and the outer edges of the side-wall portions tapering correspondingly from the center outward to merge with the tapers of the flaps to provide the side walls at the top of the container with oppositely disposed recesses tapering from near both end walls toward the bottom wall.

4. A foldable-container blank comprising a centrally disposed flat bottom-wall portion having oppositely disposed ends and oppositely disposed sides, flat end-wall portions foldably disposed along the ends and each having oppositely disposed foldable flap members constituting a first group of members, flat side-wall-portion members of substantially the same length as said bottom wall foldably disposed along the sides and constituting a second group of members, one of the groups of members each having a tongue and the other group of members each having a tongue-receiving member for receiving one of the tongues to hold the blank, when folded, in the form of a container having outwardly flaring end walls, the bottom-wall portion constituting the flat bottom wall of the container, the end-wall portions constituting oppositely disposed flat end walls of the container, the side-wall portions and the flaps constituting oppositely disposed flat sides of the container, the outer edges of the end-wall portions constituting the outer boundaries of the end walls of the container, the outer edges of the side-wall portions and of the flaps constituting the outer boundaries of the sides of the container, the outer edges of the flaps tapering outwardly from near the outer edges of the end-wall portions and said flaps cooperating with said flat side-wall portions to form oppositely disposed recesses tapering from near both end walls toward the bottom wall.

5. A foldable-container thick-paper blank cut and scored to provide a centrally disposed flat substantially rectangular bottom-wall portion, flat end-wall portions foldably disposed along the ends of the rectangle and each having oppositely disposed foldable flaps, the outer edges of the flaps tapering outwardly from near the outer edges of the end-wall portions at one end and each terminating in a tongue at the other end,

flat side-wall portions of substantially the same length as said bottom-wall portion foldably disposed along the sides of the rectangle, the outer margins of the side-wall portions being provided with slits for receiving the respective tongues to hold the blank, when folded, in the form of a container having outwardly flaring end walls, the bottom-wall portion constituting the flat bottom wall of the container, the end-wall portions constituting oppositely disposed flat end walls of the container, the side-wall portions and the flaps constituting oppositely disposed flat sides of the container, the outer edges of the end-wall portions constituting the outer boundaries of the end walls of the container, the outer edges of the side-wall portions and of the flaps constituting the outer boundaries of the sides of the container, the outer edges of the side-wall portions tapering correspondingly to the tapering edges of the flaps from the center outward to merge with the tapering edges of the flaps to constitute with the tapering edges of the flaps and with the tongues oppositely disposed recesses in the sides of the container tapering from near both end walls toward the bottom wall.

6. A foldable-container thick-paper blank cut and scored to provide a centrally disposed flat substantially rectangular bottom-wall portion, flat end-wall portions foldably disposed along the ends of the rectangle and each having oppositely disposed foldable flaps, the outer ends of the end-wall portions being wider than their inner ends along the line of fold, the outer edges of the flaps tapering outwardly from near the outer edges of the end-wall portions at one end and each terminating in a tongue at the other end, flat side-wall portions of substantially the same length as said bottom-wall portion foldably disposed along the sides of the rectangle, the outer margins of the side-wall portions being provided with slits for receiving the respective tongues to hold the blank, when folded, in the form of a container having outwardly flaring end walls, the bottom-wall portion constituting the flat wall of the container, the end-wall portions constituting oppositely disposed flat end walls of the container, the side-wall portions and the flaps constituting oppositely disposed flat sides of the container, the outer edges of the end-wall portions constituting the outer boundaries of the end walls of the container, the outer edges of the side-wall portions and of the flaps constituting the outer boundaries of the sides of the container, the outer edges of the side-wall portions tapering correspondingly to the tapering edges of the flaps from the center outward to merge with the tapering edges of the flaps to constitute with the tapering edges of the flaps and with the tongues oppositely disposed recesses in the sides of the container tapering from near both end walls toward the bottom wall.

7. A container formed from a foldable-container blank, the container having a flat stable bottom wall upon which the container is adapted to rest stably, the bottom wall having oppositely disposed ends and oppositely disposed sides, the container having oppositely disposed substantially trapezoidal flat outwardly flaring end walls formed by folding the blank along the ends of the bottom wall at an obtuse angle to the bottom wall and oppositely disposed central portions of flat side walls of substantially the same length as the length of the sides formed by folding the blank along the sides of the bottom wall substantially at right angles to the bottom wall,

whereby the container has substantially the shape, in longitudinal cross-section, of an equilateral trapezoid, with the bottom wall at the shorter base of the trapezoid, the container being open along the longer base of the trapezoid, the end walls being wider at the top than at the bottom, each end wall having oppositely disposed flaps folded to constitute end portions of the side walls, the central portions of the side walls being provided with means for cooperating with the flaps to hold the flaps to the central portions of the side walls in order that the central portions of the side walls and the flaps may constitute the side walls of the container, and the outer edges of the flaps tapering from near the outer edges of the end walls and the outer edges of the central portions of the side walls tapering correspondingly from the center outward to merge with the tapering edges of the flaps to provide the side walls at the top of the container with oppositely disposed recesses tapering from near both end walls toward the bottom wall of the container.

8. A container formed from a foldable-container blank, the container having a flat stable bottom wall upon which the container is adapted to rest stably, the bottom wall having oppositely disposed ends and oppositely disposed sides, the container having oppositely disposed flat outwardly flaring end walls formed by folding the blank along the ends of the bottom wall and oppositely disposed central portions of flat side walls of substantially the same length as the length of the sides formed by folding the blank along the sides of the bottom wall, each end wall having oppositely disposed flaps folded to constitute end portions of the side walls, each flap having a tongue, the central outer portions of the side walls each having a tongue-receiving member for receiving one of the tongues to hold the flaps to the central portions of the side walls in order that the central portions of the side walls and the flaps may constitute the end walls of the container, and the outer edges of the flaps tapering from near the outer edges of the end walls and the flaps cooperating with the flat side walls to form oppositely disposed recesses tapering from near both end walls toward the bottom wall of the container.

9. A container formed from a foldable-container blank, the container having a flat stable substantially rectangular bottom wall upon which the container is adapted to rest stably, the container having oppositely disposed flat outwardly flaring end walls formed by folding the blank along the ends of the rectangle and oppositely disposed central portions of flat side walls of substantially the same length as the length of the sides formed by folding the blank along the sides of the rectangle, the end walls being wider at the top than at the bottom, each end wall having oppositely disposed flaps folded to constitute end portions of the side walls, each flap having a tongue, the outer margins of the central portions of the side walls being provided with slits for receiving the respective tongues to hold the flaps to the central portions of the side walls in order that the central portions of the side walls and the flaps may constitute the side walls of the container, the outer edges of the flaps tapering from near the outer edges of the end walls and the outer edges of the central portions of the side

walls tapering correspondingly from the center outward to merge with the tapering edges of the flaps to constitute with the tapering edges of the flaps and with the tongues oppositely disposed recesses in the sides of the container tapering from near both ends toward the bottom wall of the container.

10. A container formed from a foldable-container blank, the container having a flat stable bottom wall upon which the container is adapted to rest stably, the bottom wall having oppositely disposed ends and oppositely disposed sides, the container having oppositely disposed flat outwardly flaring end walls formed by folding the blank along the ends of the bottom wall and oppositely disposed central portions of flat side walls of substantially the same length as the length of the sides formed by folding the blank along the sides of the bottom wall, each end wall having oppositely disposed flap members folded to constitute end portions of the side walls, the flap members constituting a first group of members, the central portions of the side walls constituting a second group of members, one of the groups of members each having a tongue and the other group of members each having a tongue-receiving member for receiving one of the tongues to hold the flaps to the central portions of the side walls in order that the central portions of the side walls and the flaps may constitute the side walls of the container, and the outer edges of the flaps tapering from near the outer edges of the end walls and the flaps cooperating with the flat side walls to form oppositely disposed recesses tapering from near both end walls toward the bottom wall of the container.

11. A sandwich container formed from a foldable-container blank, the container having a stable flat bottom wall upon which the container is adapted to rest stably, the bottom wall having oppositely disposed ends and oppositely disposed sides, the container having oppositely disposed flat outwardly flaring end walls formed by folding the blank along the ends of the bottom wall and oppositely disposed central portions of flat side walls of substantially the same length as the length of the sides formed by folding the blank along the sides of the bottom wall, each end wall having oppositely disposed flaps folded to constitute end portions of the side walls, the central portions of the side walls being provided with means for cooperating with the flaps to hold the flaps to the central portions of the side walls in order that the central portions of the side walls and the flaps may constitute the side walls of the container, the outer edges of the flaps tapering from near the outer edges of the end walls and the flaps cooperating with the flat side walls to form oppositely disposed recesses tapering from near both end walls toward the bottom wall of the container, a sandwich being adapted to be confined in the container by the bottom wall, the end walls and the unrecessed portions of the side walls, the drippings from the sandwich being adapted to be collected in the bottom of the container between the lower portions of the end walls and the lower unrecessed portions of the side walls, and the unrecessed portions of the side walls providing an area for gripping the container with the sandwich therein.

CERTIFICATE OF CORRECTION.

Patent No. 2,367,675.

January 23, 1945.

RICHARD JAMES GREENLEAF, II.

It is hereby certified that error appears in the printed specification of the above numbered patent requiring correction as follows: Page 2, first column, line 22, for "container" read --containers--; page 3, second column, line 44, claim 6, after "flat" insert --bottom--; page 4, first column, line 43, claim 8, for "end" read --side--; and second column, line 65, for "adatped" read --adapted--; and that the said Letters Patent should be read with this correction therein that the same may conform to the record of the case in the Patent Office.

Signed and sealed this 24th day of April, A. D. 1945.

Leslie Frazer

(Seal)

Acting Commissioner of Patents.
